(57) **CLAIM**

The ornamental design for a chair, as shown and described.

DESCRIPTION

FIG. 1 is a front perspective view of the design;

FIG. 2 is a rear perspective view of the design;

FIG. 3 is a left side elevation view thereof (with the right side being identical); and,

FIG. 4 is a rear elevation view thereof.

The portions of the chair shown in broken lines are provided for illustration purposes only and form no part of the claimed design.

1 Claim, 2 Drawing Sheets

FIG. 4

FIG. 3
